KNITTING MACHINE STOP MECHANISM

David Pernick, Brooklyn, N. Y.

Application July 12, 1952, Serial No. 298,509

12 Claims. (CL 66—166)

1

The present invention relates to knitting machines of the flat bed type, such as tricot and raschel machines and the like, and more particularly to knock-off or stop mechanism for such machines.

One of the problems in the knitting of fabric is the waste occasioned by defects in the fabric. This is particularly serious in connection with knitting machines of the tricot type which have a very wide bed and are operated at high speeds, because one improperly formed stitch in a course renders a wide piece of fabric defective. In the event improper stitch formation is caused by breakage of a needle hook, which frequently occurs at high speed operation, a considerable length of fabric having imperfections may be knitted before the operator detects the same and can stop the machine.

Accordingly an object of the present invention is to provide means for automatically detecting improper stitch formation and stopping the knitting machine in the event thereof.

Another object is to detect the absence of a stitch or loop on the shank of the needles at a moment in the knitting cycle when the stitch or loop should be on the shank.

Another object is to provide mechanism of the foregoing character which can be readily incorporated in newly built machines and can also be installed on existing machines.

A further object is to accomplish the foregoing by providing mechanism which is simple and economical in construction and is practical in operation.

Other and further objects will be obvious upon an understanding of the illustrative embodiment about to be described, or will be indicated in the appended claims, and various advantages not referred to herein will occur to one skilled in the art upon employment of the invention in practice.

In accordance with the present invention, the foregoing objects may be accomplished by providing knock-off or stop mechanism comprising in combination an electrically operated device adapted to effect stoppage of the knitting machine; an electrically conductive needle bar having conductive needles thereon and in electrical contact therewith; switch elements mounted on the needle bar, but electrically insulated therefrom, having a yieldable portion in electrical contact with a needle shank at a zone where the loop of a stitch should be disposed at a predetermined moment in the knitting cycle, whereby the presence of a loop at the zone will break the con-

2

tact between the switch element portion and the needle shank; a source of electrical energy for the device; and means for establishing a circuit from the source through the switch element, the needle bar and the device, including a normally open switch, and means for closing the switch only at the predetermined moment in the knitting cycle when the loops of the stitches should break the contact between the yieldable switch element portions and the needle shanks, whereby, in the absence of one or more loops at such moment, the device is energized to effect stoppage of the machine.

A preferred embodiment of the invention has been chosen for purposes of illustration and description and is shown in the accompanying drawing, forming a part of the specification, wherein:

Fig. 1 is an elevational view wherein a portion of a needle bar and a pair of knitting needles are shown as seen from the back of the machine and a switch element is associated with each of the needles.

Fig. 2 is a side view, partly in section and partly in elevation, illustrating the loop of a stitch in a position on the needle shank to break the contact between the switch element and the needle.

Fig. 3 is a view similar to Fig. 2, illustrating the stitch in a position just prior to breaking the contact and including a wiring diagram which illustrates the manner in which the knock-off mechanism is controlled by the switch means associated with the needle.

Referring to the drawing in detail and more particularly, to Figs. 1 and 2 thereof, there is shown a portion of a needle support 10, which for purposes of explaining the invention may be considered a portion of the needle bar of a flat bed knitting machine, and a pair of needles 11 each having its shank 12 mounted in the support. The support may be any of the well-known types utilized in connection with such machines, although the same is shown herein as a lead block 10 having the needles shank cast therein. In any event, the needle and the support are electrically conductive and are in electrical contact with the needle bar proper or a common conductor associated with the needle bar.

Only two needles are shown, for purposes of illustration, but it will be appreciated that hundreds of such needles are usually mounted on the needle bar. Also, while the needle shown herein is of the type known as a bearded needle, it will be understood from the following description

that the present invention may be practiced in connection with other types of needles including latch needle, plush points and the like.

A switch element 14 is mounted on the needle support which has a yieldable portion 15 normally in electrical contact with the needle shank at a point or zone where the loop L of a stitch should be disposed at a predetermined moment in the knitting cycle. The yieldable portion preferably has a straight section 16 adjacent its upper end which makes contact with the needle shank along a length thereof coextensive with the zone where the loop may be located. Preferably, the yieldable portion causes the section 16 to engage the needle shank under very light spring tension sufficient to establish an electrical connection but without offering undue resistance to the loop, whereby fraying of the yarn does not occur. The free end 17 of the yieldable portion extends away from the needle shank to form a wedge which facilitates positioning the loop between the section 16 and the needle shank and further minimizes frictional forces acting on the yarn.

The element 14 may be mounted on the needle support in any suitable manner. For example, a plurality of such elements may have the end opposite the free end in electrical contact with a common conductor which extends lengthwise with the needle bar. As shown in the drawing, each element is secured to a bar 19 which is attached to the needle support but is electrically insulated therefrom by a strip 20 of non-conductive material, such as Bakelite or the like. It will be appreciated that the elements could be stamped from a metallic strip to form a comb-like structure wherein all the elements extend like teeth from a continuous strip which serves as the common conductor.

In Fig. 3, the needle and switch element associated therewith is shown in electrical connection with means for effecting stoppage of the knitting machine in the event a loop does not break the contact between the switch element and the needle at the predetermined moment in the knitting cycle. Such means include an electrically operated knock-off mechanism 25 of any known type, a source of electrical energy, herein shown as a transformer 26, for supplying current at a low voltage, and a normally open switch 27.

As shown, one leg of the secondary of the transformer is connected to one side of the knock-off mechanism 25, the other side of this mechanism is connected to the needle bar 10, the switch elements are connected through the conductor 19 to one side of the switch 27, and the other side of the switch is connected to the other secondary leg of the transformer.

In order to establish an electrical circuit and energize the knock-off mechanism in the event a loop fails to be disposed between the switch element section 16 and the needle shank at the predetermined moment, mechanism is provided for closing the switch 27 at such moment. Such mechanism includes a cam 29 driven in synchronism with the knitting elements of the machine which has one or more projections 30 thereon for effecting closing of the switch 27 at the exact moment a loop L should be at the desired zone along the needle shank.

For example, in Fig. 3 the loop shown is just about to be drawn between the switch element section 16 and the needle shank, and the projection 30 is just about to effect closing of the

switch 27. Thus, should the loop break or for any other reason fail to reach the proper zone on the shank, there will be electrical contact between the needle and the switch element and closing of the switch 27 will then complete the knock-off mechanism energizing circuit. Should the loop be properly positioned at the desired moment, as shown in Fig. 2, closing of the switch does not cause the mechanism to be energized because the circuit is open between the needle and the switch element.

While only one needle and switch element have been shown, it will be appreciated that if hundreds of the same are electrically connected in the circuit in the same manner, the failure of any single switch element to be separated from its needle will cause energization of the knock-off mechanism at the predetermined moment. Likewise, if all needles have a loop thereon at such moment, which breaks the contact between the needles and the switch elements, the circuit is open when the switch 27 is closed.

From the foregoing description, it will be seen that the present invention provides a novel and useful arrangement of devices for detecting improper stitch formation and automatically effecting stoppage of the knitting machine instantaneously, whereby very little fabric and yarn are wasted.

As various changes may be made in the form, construction, and arrangement of the parts herein, without departing from the spirit and scope of the invention and without sacrificing any of its advantages, it is to be understood that all matters are to be interpreted as illustrative and not in any limiting sense.

What is claimed is:

1. In stop mechanism for knitting machines of the class described, the combination of an electrically operated device adapted to effect stoppage of the machine, an electrically conductive needle bar having a conductive needle thereon in electrical contact therewith, a conductive bar, an insulator interposed between said needle bar and said conductive bar, a switch element having a base portion mounted on said conductive bar and having a yieldable portion in electrical contact with the shank of said needle at a zone where the loop of a stitch is disposed at a predetermined moment in the knitting cycle, whereby the presence of a loop at the zone will break the contact between said portion and the needle shank, a source of electrical energy for said device, means for establishing a circuit from said source through said switch element, said needle bar, and said device including a normally open switch, and means for closing said switch only at said moment in the knitting cycle when a loop of the stitch should break the contact between said yieldable portion and the needle shank, whereby in the absence of a loop at said moment said device is energized to effect stoppage of the machine.

2. Mechanism according to claim 1, wherein said switch closing means are operated in synchronism with movement of said loop.

3. Mechanism according to claim 1, including a plurality of said needles, a switch element for each needle and means electrically connecting all of said switch elements, whereby said device is adapted to be energized in the absence of a loop on any of said needle shanks.

4. In stop mechanism for knitting machines of the class described, the combination of an electri-

cally operated device adapted to effect stoppage of the machine, an electrically conductive needle bar having a conductive needle thereon in electrical contact therewith, a conductive bar, an insulator interposed between said needle bar and said conductive bar, a switch element having a base portion mounted on said conductive bar and having a yieldable portion in electrical contact with the shank of said needle, a normally open switch, means for closing said switch at a predetermined moment in the knitting cycle, a source of electrical energy, means for connecting one side of said source to one side of said switch, means for connecting the other side of said switch to said switch element, means for connecting said needle bar to one side of said device, and means for connecting the other side of said device to the other side of said source.

5. In a knitting machine of the class described, the combination of an electrically conductive needle bar, a knitting needle on said bar in electrical contact therewith, switch means including a yieldable portion in electrical contact with the shank of said needle, means for mounting said switch means on said needle bar, and electrically insulating means interposed between said switch means and said needle bar.

6. In a knitting machine of the class described, the combination of an electrically conductive needle bar, a plurality of knitting needles on said bar in electrical contact therewith, and switch means including a conductive strip portion extending lengthwise along said bar, an insulating strip between said conductive strip portion and said bar, and including a plurality of yieldable conductive portions each in electrical contact with

one of said needles and in electrical connection with said conductive strip portion.

7. Apparatus according to claim 6, wherein said yieldable portions are individually removably connected to said conductive strip portion.

8. In a flat bed knitting machine, the combination of a plurality of needles and a switch element for each of said needles having a portion engaging the shank of a needle and adapted to be moved out of contact therewith by the loop of a stitch on the shank.

9. In a stop mechanism circuit for knitting machines of the class described, the combination of an electrically operated device adapted to effect stoppage of the machine, switch means operable by a loop of a stitch to open the same, a normally open switch, and means for closing said switch at the moment the loop is adapted to open said switch means.

10. In a knitting machine of the class described the combination of a needle having a shank, and a switch element having a portion normally in engagement with said shank at a predetermined zone.

11. In a machine according to claim 10, wherein said element has a straight section contacting said shank at a zone along the length thereof.

12. In a machine according to claim 11, wherein said element has a free end portion which extends away from said shank to provide a wedge.
